COLD CHISEL OR THE LIKE

Delbert L. Farmer, Norwood, Ohio, assignor to The Cincinnati Tool Company, Cincinnati, Ohio, a corporation of Ohio

Application April 5, 1957, Serial No. 45,614

Term of patent 14 years

(Cl. D93—4)

The dominant feature of the design resides in those portions which are shown in full lines.

The opposite side of the chisel, not shown in Figure 2, is substantially identical with the side shown.

I claim:

The ornamental design for a cold chisel or the like, substantially as shown and described.
